JOSEPH C. COULOMBE, OF LOWELL, MASSACHUSETTS.

SUCTION-INDUCING AND FUEL-FEEDING DEVICE.

1,365,661.

Specification of Letters Patent. Patented Jan. 18, 1921.

Application filed July 19, 1918. Serial No. 110,010.

To all whom it may concern:

Be it known that I, JOSEPH C. COULOMBE, a citizen of the United States, and a resident of Lowell, in the county of Middlesex and State of Massachusetts, have invented certain new and useful Improvements in Suction-Inducing and Fuel-Feeding Devices, of which the following is a specification.

The invention relates to the feeding of a liquid from a point above the source of supply to a lower point, through the action of suction inducing means produced by the apparatus in conjunction with which the feeding apparatus is combined.

15 It relates more particularly to an apparatus having a new principle of operation, as compared with my co-pending application, Serial No. 32,927, filed June 8, 1915, and involves the use of the vacuum produced in

20 the manifold in conjunction with the vacuum produced at the exhaust side of a gas engine as will be more fully described hereinafter.

The object of the invention is to provide 25 a means for producing suction or vacuum in conjunction with a feeding apparatus by utilizing the exhaust velocity of gases or vapors through the use of an ejector.

A further object is to provide a means for 30 increasing the suctional action and its efficiency by decreasing the weight of the liquid column which must be raised thereby.

A still further object is to arrange a mechanism dependent upon the manifold suction 35 in conjunction with the exhaust action which will simplify the parts of the feed apparatus that are in direct control of the fuel which is to be raised from the source of supply and fed to the carbureter or other 40 device of the engine.

In devices heretofore used and such as described in my co-pending application, Serial No. 32,927, filed June 8, 1915, the suction induced at the manifold or at a point above 45 the carbureter of an engine has been utilized in conjunction with a chamber or chambers controlled by valves for maintaining a suction until a predetermined volume of liquid was drawn into the chamber. Thereupon, 50 through float devices or other apparatus, the vacuum or suction was broken, and the contents of the vessel was permitted to flow onward and finally reach the carbureting mechanism.

55 The present invention has to do with an arrangement which will do away with air

valves and complicated devices in the suction and distributing chambers of the heretofore described and known devices, and will give an efficient supply of fuel at all times and under all conditions of operation of the engine.

Referring to the drawings:

Figure 1 is a somewhat diagrammatic view illustrating the connections and appurtenant parts between a fuel tank, fuel feeding device and the carbureter of an engine.

Fig. 2 is a sectional view of a distributing tank.

Fig. 3 is a detail sectional view of the 70 connections between the manifold suction, exhaust suction and the distributing tank.

Fig. 4 is a detail sectional view of a form 75 of connection in the exhaust side of the engine.

Fig. 5 is a detail sectional view of the supply tank and connections.

Fig. 6 is a similar detail view of a modified form of arrangement of supply tank.

As is well known in the art, it is not new 80 to employ the suction or vacuum produced at the manifold to raise fuel from a low point to a high point in order that it may be fed to the carbureter. Such systems and apparatus rely upon a suction produced in 85 the manifold by the action of the pistons of an engine, and the suction effect is ordinarily controlled in the distributing chamber by a float which actuates valves, so that the vacuum will be broken through the opening 90 of an air valve upon a certain rise of liquid in the chamber to permit passage of said liquid out of the distributing chamber or tank.

In such devices reliance is placed upon the 95 suction in the manifold, which suction obviously is an extremely variable quantity and depends entirely upon the variability of suction in the manifold. For instance, when the throttle of the engine is wide open there 100 is a material decrease in suction at a time when there should properly be an increased suction to draw up fuel into the distributing chamber, inasmuch as the engine on a wide open throttle requires a greater amount of 105 fuel than when running with a closed throttle.

In other words, the balance which is required in the distributing chamber has been 110 dependent entirely upon the suction induced in the manifold and this, being a variable suction dependent on manipulation of the

engine, has resulted in an extremely variable condition as regards the operation of the distributing chamber.

In the present invention there is such a distributing chamber, as heretofore referred to, into which, from a source of supply, there is drawn a quantity of fuel and from which the fuel is distributed or permitted to flow to the carbureting apparatus.

10 This chamber, however, is subject to the suction induced in the manifold and is also subject to a suction effect which is produced in the exhaust of the engine.

It relies for its action very largely upon 15 the variations in exhaust pressures and, obviously, the exhaust pressures of an engine are the greatest when the engine throttle is wide open. This condition will give a proper suction when there is the least suction action in the manifold.

20 It follows that when one suction is at its maximum, the other is at its minimum, and by providing a device in the system as hereinafter described to secure the greatest balance between these two factors, a substantially perfect action is provided for the suction of the distributing tank.

Referring to the drawings, the numeral 1, denotes a manifold of an engine having a 30 carbureter 2, of any suitable type.

There is a distributing tank 3, located above the level of the carbureter and engine and a main supply tank 4, ordinarily located below the distributing tank and below 35 the carbureter. The engine is illustrated as having an exhaust pipe 5, with the usual muffler 6.

For producing suction in the tank 3, there is a connection 7, to a valve fitting 8, which 40 fitting is located between the tank 3, and the manifold 1.

It has a connection 9, with the manifold and a connection 10, with an ejector upon the exhaust system of the engine.

45 Each of the connections 9 and 10, where they enter the fitting 8, are controlled by ball or other suitable check valves of an automatic type 11, 12, so that whether the suction from the manifold through the connection 9, or that through the connection 10 is predominant, each will have its individual predominant action through the connection 7, upon the tank 3.

The connection 10, terminates in an ejector 13, which is shown in detail in Fig. 4, and is arranged in a shunt pipe 14, extending out of the exhaust pipe 5, at or near its connection with the engine and terminating beyond the muffler 6, as in the tail pipe 15.

60 This ejector 13, is designed to act in conjunction with the exhaust gases, which gases passing into it will be ejected through a bell-shaped contracted nozzle 16, and will then expand and enter a bell-shaped receiving nozzle 17, from which they will pass into

a Venturi nozzle 18, emerging through the connection 14, to the tail pipe or connection 15.

There is a special advantage in this arrangement in that the initial shunt line for 70 gases from the exhaust pipe 5, will pass through the ejector exerting there initial pressure, and this will be enhanced by the suction action at the tail pipe 15. Thus, the 75 suction at the connecting point 19, of the connection 10, will be materially increased over the suction induced by the velocity of the gases passing through the fitting 8, and its nozzle 16.

The suction produced by this ejector fitting 80 will increase with the increase of exhaust pressures, and the increase is the greatest when the engine throttle is wide open.

On the other hand, the suction induced from the manifold 1, and the connection 9, 85 will be at a minimum when the engine throttle is wide open and will be at a maximum when the throttle is substantially closed.

It follows that when the suction at the manifold is at a minimum the ejector 13, 90 will be at a maximum and vice versa. It follows that there will be a substantial suction upon the tank 3, under all conditions of operation of the engine. The unbalanced or differential suctions between the manifold 95 and fitting 13, will be taken care of by the valves 11, 12, in the fitting 8.

When the engine is laboring and turning over very slowly the suction, even with the throttle wide open, which is induced through 100 the exhaust ejector may be at a minimum. This, of course, is due to the lapse of time between explosions and although each explosion may furnish a full maximum of suction in the ejector 13, it will lose a great 105 deal of its suction effect on the tank 3, due to the lapse of time between explosions. Under this condition, the average suction produced between the high point and low point may not always be quite sufficient to 110 raise the column of fuel from the supply tank 4, by direct suction lift.

To counteract this condition, it is desirable to lighten the column of fuel existing between the supply tank 4, and distributing 115 chamber 3, by interposing therein certain volumes of air.

It is to be understood that the level of fuel in the distributing tank 3, is controlled within reasonable limits by a float 3^a, which 120 has a valve 3^b, that controls the inlet connection 3^c, which communicates with the main supply tank or source 4.

In order to provide a lightening of the weight of the column of fuel between the 125 supply tank 4 and distributor 3, to overcome the difficulties of suction lifts above referred to, the connecting pipe 3^c, is brought well into the bottom of the tank 4, and terminates in a bell-shaped end or mouth 20. Into 130

this bell-shaped mouth is introduced the end of an air tube 21, connected to the atmosphere as at 22.

Suction induced in the distributing chamber 3, is effective upon the connecting pipe 3^c, and this suction will draw in alternate volumes of air and fuel with the result that the column in the pipe line 3^c, will have alternate layers of air and liquid, thus substantially lightening the column in the pipe as compared with said column when filled with liquid. For example: If the relative volumes of air and liquid are substantially equal, the weight of the total column is only 15 half as great as it would be were it solid liquid. If the air bubbles predominate and were three times as large as the liquid bubbles, the total column would be approximately four times lighter, thereby requiring 20 only one fourth as much suction to raise the column for a given height.

The main supply tank 4, is presumed to have a substantially airtight cap 23, and, of course, as the liquid level in said tank 25 drops, air bubbles will enter the tank through the pipe 21, and bell 20. This is entirely an automatic action.

In Fig. 6 there is a slight modification of the device shown, in which there is an air vent 24, provided in the cap 23. In this case, however, the open or bell-shaped end 25, of the connecting pipe 3^c, and the extended U-shaped end 26, of the atmospheric tube 21, must be carried up above any possible height of liquid of the tank 4, so that air bubbles will not enter the bottom of the tube 25, but will enter at the restricted portion of the bell-shaped end thereof, where they are admitted by the U-shaped atmospheric 40 tube 21.

It will be understood from the above that there is a variable condition substantially automatic in its action for inducing a suitable suction in the distributing tank 3, 45 whether said suction is induced directly from the manifold or from the exhaust side of the engine. It is apparent that the connection 2^a, between the distributing tank 3 and carbureter must be of a sufficient size to 50 take care of air bubbles while it is delivering its fuel to the carbureter. It is also quite apparent that there must be a proper ratio existing between the height of the tank 3, the supply tank 4, and the carbureter 2. 55 For instance, the tank 3, must be located at a sufficient height above the carbureter so that the liquid column in the pipe 2^a, will be at least one half the height of the column in the pipe 3^c, from the supply tank 4, to the 60 distributing tank 3. The liquid volumes in this case must be equal to the air volumes, so that the total weight of the column in the pipe 3^c, has been lightened one half. That is, the weight of the column in the pipe 2^a, 65 must be greater than the weight of the col-

umn in the pipe 3^c. With alternate bubbles of air and liquid of equal volume, the rise from the tank 4, to the tank 3, can be twice as great as the drop from the tank 3, to the carbureter 2. In practice, with the suction 70 connection 7, having an orifice of approximately .040 inch in diameter and fuel pipes 2^a, 3^c, of $\frac{3}{8}$ inch diameter and a rise from the carbureter to the chamber 3, of at least one half or more than the height of the 75 rise from the tank 4, to the chamber 3, satisfactory operation will be attained with air and liquid bubbles of equal volume in the pipe 3^c. The tank 3, must always be located at such a height and the proportions 80 of the pipe line 9, and pipe line 3^c, must be such that the weight of liquid in the column of the pipe line 2^a, is slightly greater than in the pipe line 3^c. Wide latitude may be given to this condition by varying the design to provide air bubbles of greater or less size in the pipe line 3^c. The operation 85 of the device will be obvious. There is a continuous suction in the distributing tank 3, which draws up fuel from the tank 4, 90 through the pipe 3^c, the column of liquid being lightened by the air bubbles. Fuel will flow to the carbureter through the pipe 2^a, while fuel is being drawn into said tank, due to the fact that the column of fuel being raised is lighter than the column of fuel 95 leading to the carbureter. Whenever the suction in the distributing chamber 3, is greater than the weight of the solid column in the pipe 2^a, (which can occur when the 100 valve 3^b, is closed) a small quantity of air is drawn up through the pipe 2^a, from the carbureter bowl. This reduces the vacuum in the suction chamber, allowing more fuel to flow to the carbureter. There is, of 105 course, an intermittent flow to the carbureter in this instance but the intervals occur so rarely and with such rapidity of action that there is no appreciable effect noted in the action or proper functioning of the 110 carbureter.

The invention, while illustrated somewhat diagrammatically herein in one form, is of course subject to such modifications as the exigencies of any particular case require; 115 and the details may be varied to a considerable extent so long as there is a double acting and compensating suction provided for the distributing chamber, which will be active with the throttle wide open or with the 120 throttle nearly closed. Of course, the same suction apparatus herein described may be applied to a distributing tank of the type illustrated in my co-pending application heretofore referred to or, in fact, to any of 125 the various types of distributing tanks used in fuel feed apparatus with marked advantages due to the constant character of the suction on closed or open throttle. However, when you use the distributing tank as 130

- illustrated herein and in conjunction with the lightened fuel column between the supply tank and distributing tank, perfect feeding action for the carburetor is secured even when the engine is idling and comparatively slight suction effect is produced at the exhaust. Obviously, it is not imperative that the suction induced by the movement of the exhaust gases shall be secured through an individual pipe line and ejector as the ejector might be arranged directly in the exhaust pipe line. In fact, the fittings may be designed and arranged in any suitable manner to effect the novel results set forth.
- 15 What I claim as my invention and desire to secure by Letters Patent is:
1. In a fuel feeding device for engines, a source of fuel supply, a distributing chamber located above said source, and a fuel supply conduit from the source of fuel to the distributing chamber, means for subjecting said distributing chamber to suction induced in the manifold of the engine, means for inducing suction in said chamber through the movement of the exhaust gases of the engine, and a float controlled valve in the distributing chamber for controlling the fuel supply conduit.
  2. In a device of the character described, a source of fuel supply, a distributing chamber located above said source and receiving its supply therefrom, a valve controlled suction connection between the distributing chamber and the intake side of the engine, and a valve controlled suction connection between the distributing chamber and the exhaust side of the engine.
  3. In a device of the character described, a supply tank, a distributing chamber located above said tank and receiving its supply of fuel therefrom, means for inducing suction in said distributing chamber including a shunt pipe connected with the exhaust

line of the engine in front of and at the rear of the muffler, an ejector arranged in said shunt line and connections from said ejector to the distributing chamber.

4. In a fuel feeding device for engines, a fuel supply tank, a distributing chamber located above said tank and receiving its supply therefrom, a carburetor located below said distributing chamber and above the fuel tank, a connection from the fuel tank to the distributing chamber, a connection from the distributing chamber to the carburetor, a suction connection for the distributing chamber, a connection therefrom to the inlet side of the engine and a connection therefrom to the exhaust side of the engine, and means for intermittently introducing volumes of air to the connection from the fuel tank to the distributing chamber whereby the weight of the column of liquid in said connection is lightened.

5. In a fuel feeding device for engines, a source of fuel supply at a low level, a distributing chamber located above said source and receiving its supply therefrom, a carburetor located below said chamber and above the fuel tank and connected with said distributing chamber, and means for introducing a suction in said distributing chamber, said means comprising an ejector, said ejector having its inlet side connected with the exhaust pipe of the engine approximately near the engine and its exhaust side connected with said exhaust pipe substantially remote from the engine, whereby an ejector and suction effect are produced upon the ejector by the movement of the exhaust gases, and a connection from said ejector to the suction chamber.

JOSEPH C. COULOMBE.
